SPARK PLUG

Charles Lehman and Otto E. Lehman,
Philadelphia, Pa.

Application July 12, 1934, Serial No. 734,766

7 Claims. (Cl. 123—169)

Our invention relates to new and useful improvements in a spark plug and has for one of its objects to provide an exceedingly simple and effective device of this character which is relatively inexpensive in the cost of manufacture although strong and durable.

Another object of this invention is to provide an air-cooled spark plug having a spacious air chamber extending substantially from one end to the other.

Another object of the present invention is to so construct the spark plug that it will be oil, heat and carbon resisting.

Another object of the invention is to provide a spark plug including a body closed at its lower or inner end except for an opening through which the porcelain protrudes, said opening being closed by the porcelain and a gasket on which a shoulder of the porcelain is seated, thereby preventing the influx of oil to the body or shell, which oil often accumulates and produces incrustations of carbon.

A further object of our invention is to provide, in combination, a spark plug having a central electrode, and a unique means for attachment of a cable terminal thereto.

A still further object of the invention is to construct a spark plug including a central electrode connected with a head, the latter being fashioned so as to prevent rotation thereof in the porcelain core and having a spring pressed clamping washer provided with a concavo-convex rib for coaction a specially shaped cable terminal.

With these and other ends in view, this invention consists of the details of construction and combination of elements hereinafter set forth and then specifically designated by the claims.

In order that those skilled in the art to which this invention appertains may understand how to make and use the same, we will describe its construction in detail, referring by numerals to the accompanying drawing forming a part of this application, in which:—

Fig. 1 is a side elevation of a spark plug constructed in accordance with our invention.

Fig. 2 is a longitudinal or vertical section thereof, with the central electrode and its component parts shown in elevation.

Fig. 3 is a view of the upper end of the central electrode and the attachable head structure thereon.

Fig. 4 is an upper end view of Fig. 1.

Fig. 5 is a section at and on the line 5—5 of Fig. 2.

Fig. 6 is a section at and on the line 6—6 of Fig. 2, and

Fig. 7 is a section at and on the line 7—7 of Fig. 2.

In carrying out our invention as herein embodied, 10 represents the body or shell of the spark plug provided with a shank 11, which has external threads 12, for mounting the spark plug in the cylinder of an engine.

Within said body or shell is formed a spacious 10 air chamber 13, preferably larger at its upper end than at its lower or inner end and in the lower or inner end of the body or shell is produced a longitudinal hole 14, for a purpose to be presently described, and said hole communicates with the 15 air chamber.

In the side walls of the body or shell are a number of transverse or radial apertures 15 which communicate with the upper part of the air chamber and function as air inlets and outlets. 20

A porcelain core 16 is inserted into the air chamber through the upper end of the body or shell and said core has a reduced lower end 17 which projects through the hole 14. Said reduced end of the porcelain core is of a size that snugly 25 fits the hole 14, but has sufficient tolerance to permit expansion of the parts, whereby the hole is partly closed to prevent the entrance of oil into the oil chamber. The closure is made complete by a gasket 18, resting on a seat 19 within the body or shell, and the shoulder 20 formed by the differences in diameter of the reduced end and the contiguous part of the core.

An intermediate part of the core, which is located within the body or shell, is also reduced in 35 diameter for substantially the length of the air chamber so that only a limited amount of the space of the air chamber will be occupied, leaving a large space for the circulation of air. The porcelain core is held in place by a gland nut 21 40 which engages a shoulder 22 on the core and has threaded engagement with the body or shell.

In the longitudinal center of the porcelain core is the central electrode 23 and the lower end of 45 said electrode protrudes beyond the lower end of the core in proximity to the return or ground electrode 24. The end of the porcelain core from which the lower end of the central electrode protrudes is convex so that any liquid reaching 50 the same will readily flow or drip therefrom.

On the upper end of said central electrode 23 is mounted a head 25, consisting of a post 26 which originally is preferably round in cross section throughout its entire length and with a reduced upper or outer end portion 27 to provide 55

a shoulder 28. On the post 26, intermediate its ends, is a collar 29, approximately the same diameter as the upper or outer end of the porcelain core, against which it rests. The lower end 5 of the post has a hole in it to receive the upper end of the central electrode and after the parts are assembled, said lower end of the post is swaged into an angular relatively thin and wide skirt 30, thereby fixing the head to its electrode. This 10 skirt is embedded in the porcelain core and prevents the head from turning relative to said core.

A clamping washer 31 is slidably and rotatably mounted on the post 26 and has a concavo-convex rib formed therein to provide a diametrical groove 15 32 in the under or inner face of said clamping washer, with portions of said groove on opposite sides of the post. This clamping washer is forced toward the collar 29 by a spring 33 positioned between the washer and a cap 34, mounted on the outer end of the post. Preferably, the cap is placed on the reduced outer end of the post in contact with the shoulder 28 and said post then set up as a rivet head, as at 35.

A connecting terminal 36, Figs. 1 and 4, is provided for use with the attaching structure and is to be fastened to a cable or other electrical conductor. This terminal has the usual legs to straddle the post and each leg is provided with a transverse ridge or projection 37 for registration with the groove 32. The ridge 37 and the groove 32 are so shaped that when sufficient force is applied, the terminal 36 can be readily attached or detached, but accidental separation is prevented. Since the clamping washer is loose 30 on the post, and since the terminal only rests on the collar, said terminal may be turned around the post into any desired position without detaching the same.

From the foregoing it will be obvious that 40 when the spark plug is in use no oil can enter the lower part of the body or shell, thereby eliminating one of the causes of electrical leakage and the formation of carbon deposits. As heat also enters into the cause of the formation of 45 carbon, the chance of such formation is further reduced to a minimum by providing means to cool the parts of the spark plug as above described.

By using the construction herein described, 50 especially in connection with automobile and airplane engines, air will be forced toward the spark plug or plugs by the cooling fan or propeller. The air will enter some of the apertures 15 and circulate about the spacious air chamber 13 and then exit through others of said apertures 15. Because of the spaciousness of the air chamber, large 55 quantities of air can circulate and will maintain the parts of the spark plug which are subjected to high degrees of heat, at a relatively low and even temperature.

Of course we do not wish to be limited to the exact details of construction herein shown and described as these may be varied within the scope of the appended claims without departing from 60 the spirit of our invention.

Having thus fully described our invention, what we claim as new and useful, is:—

1. A spark plug comprising a body or shell having a threaded portion and provided with a spacious air chamber extending from adjacent the upper to adjacent and past the lower threaded portions of the body with a longitudinal hole in the bottom and radial apertures in the side walls communicating with the air chamber, a core of 70 insulating material mounted in the body or shell

and having a reduced end fitted in the bottom hole to close the same, said core having a large portion thereof within the body or shell reduced in size, a central electrode mounted in said core, and another electrode carried by the body or shell and located adjacent the inner end of the central electrode. 5

2. The structure in claim 1, in combination with a gasket located between a shoulder on the core and a seat at the bottom of the air chamber to further close the hole at the bottom of the body or shell.

3. In a device of the kind described, a body or shell including a partially threaded shank and having a spacious air chamber extending from adjacent the upper portion of the body proper to adjacent and past the threaded portion of the shank and having radial apertures in the side walls communicating with said air chamber, and a porcelain core carrying an electrode and mounted in the body or shell, said core having that portion within the air chamber considerably reduced in circumference. 15

4. A spark plug comprising an air cooled body or shell, a porcelain core in said body or shell 25 with both ends extending beyond the respective ends of said body or shell, said core substantially closing the lower end of the body or shell, means at the upper end of said body or shell to hold the core in place, a central electrode in the core, 30 a head structure including a post, a substantially triangular thin skirt swaged from the lower portion of said post and embedded in the core, the swaging of said post fixing the head structure to the electrode, a collar on said post engaging the 35 upper end of the core, a clamping washer slidably and rotatably mounted on the post and having a groove in its under face to receive a ridge on a cable connecting terminal, a cap mounted on the upper end of the post, and a spring on 40 the post between the cap and clamping washer to force the latter toward the collar.

5. The structure in claim 4, wherein the cap is mounted on a reduced end of the post and contacts a shoulder produced by the differences 45 in diameters between said reduced end and the contiguous portion of the post and wherein said cap is held in place by a rivet head formed on the end of the post.

6. In a spark plug, a porcelain core, a central 50 electrode in said core, a head structure including a post having a reduced upper end, a shoulder at the junction between said reduced upper end and the contiguous part of the post, the lower end of said post having a hole for registration 55 with the upper end of the electrode, a skirt swaged from the lower end of the post to fix the head structure to the electrode and embedded in the core to prevent rotation of said head structure relative to said core, a collar on said post, 60 a clamping washer slidably and rotatably mounted on the post and forming a clamp with the collar, said clamping washer having a groove in its under face for registration with a ridge on a cable terminal, a cap mounted on the reduced 65 end of the post, a rivet head formed from the extreme outer end of the post to hold said cap in place, a spring between said cap and the clamping washer to force the latter toward the collar, a hollow body or shell having a shank for 70 projection into an engine and provided with apertures above the shank communicating with the interior of the body or shell and functioning as inlets and outlets for air, a gasket in the bottom of the body or shell, said core and asso- 75

- ciated parts being mounted in the body or shell with the lower end of said core protruding through a hole in the bottom of the body or shell, a shoulder on said core to engage the gasket and close the hole, that portion of the core within the body or shell being spaced from the side walls of the body or shell to form an air chamber, means to hold said core in the body or shell, and another electrode on the body or shell 5 for co-action with the central electrode.
- 10 7. In a spark plug, a body or shell having an air chamber extending approximately all the way from one end to the other with a longitudinal hole of smaller diameter than the air chamber in the bottom and radial apertures in the 15 side walls communicating with the upper por-

tion of said air chamber, a single seat at the bottom of the air chamber, a porcelain core mounted in the body or shell and having a reduced lower end projecting through the hole in the bottom of the body or shell, the extremity of said reduced end being convex, a shoulder on the core at the top of the reduced end for co-action with the seat, a gasket between the seat and shoulder, a central electrode embedded in the porcelain core and exposed only where it 10 protrudes from the convex lower extremity of said core, and another electrode carried by the body or shell and spaced from the central electrode.
